WILLIAM F. DIESEL, OF ROCHESTER, NEW YORK, ASSIGNOR TO SARGENT & GREENLEAF, INC., OF ROCHESTER, NEW YORK, A CORPORATION OF NEW YORK

LOCKING MECHANISM

Application filed March 2, 1926. Serial No. 91,765.

The present invention relates to locking mechanism for guarding the doors or closures of safes, vaults or other containers or compartments employed for protecting valuables of various kinds.

One object of the invention is to provide improved locking mechanism for said doors or closures whereby to delay opening of the same for a definite and predetermined period after the locking mechanism has been moved to protecting position.

Another object of the invention is to provide an improved securing mechanism for the doors or closures of safes, vaults and the like in combination with timing mechanism adapted to prevent release thereof for predetermined periods to be determined by a person in charge of or responsible for contents of the safe.

A further object of the invention is to provide an improved time controlled securing mechanism for the closures of safes, vaults or the like in conjunction with a combination or other type of lock or controlling means by which the timing mechanism is prevented from operating until said lock or controlling means is moved to release position with respect thereto.

A further object of the invention is to provide improved locking means for the closures of safes, vaults and the like embodying bolt-work or other protecting means in combination with obstructing means therefor adapted to be conditioned thereby for movement automatically to obstructing position upon movement of the bolt-work in one direction and further to provide means for controlling the operation of the obstructing means, preferably a timing mechanism for

delaying its release together with a selective control mechanism or a combination lock or other suitable means for guarding the timing mechanism, the latter serving to prevent unauthorized persons from gaining immediate access to the contents of the safe following successful operation of the combination lock or other means for controlling the timing mechanism.

A further object of the invention is to provide in conjunction with a safe or vault

securing mechanism under the control of a combination or other lock, protecting means which will automatically operate to prevent release of the securing mechanism should attempt to made to enter the safe by disabling the combination lock as by driving in the spindle thereof or by otherwise mutilating or destroying its usefulness.

A still further object is to provide improved means adapted in case where dynamite or other materials are exploded within the safe to prevent dropping or release of the bolt-work obstructing means at the time of the explosion or by subsequently jarring or moving it to release position or by the use of an instrument, the improved means being of a nature whereby as a result of the explosion relative movement will be afforded between certain parts of the mechanism and said means so that the latter will immediately occupy a protecting position with respect to the bolt work.

To these and other ends the invention resides in certain improvements and combinations of parts, all as will be hereinafter more fully described, the novel features being pointed out in the claims at the end of the specification.

In the drawings:

Figure 1 is a sectional elevation through a vault or other container looking at the inner face of the closure therefor and showing the manner of applying the present invention thereto.

Figure 2 is a side elevation, illustrating one embodiment of the invention as applied to the door of a safe or vault having a combination lock thereon.

Figure 3 is a fragmentary view in elevation looking at the front of that portion of the door shown in Figure 2.

Figure 4 is a rear elevation illustrating one embodiment of the invention with the parts shown in locking position.

Figure 5 is a similar view with the obstructing means for the bolt work shown in release position.

Figure 6 is a fragmentary view in elevation illustrating a portion of the lever for

controlling the obstructing means for the timing mechanism.

Figure 7 is a view in elevation showing the opposite side of the bolt work obstructing means from that shown in the lower part of Figure 5.

Figure 8 is a fragmentary elevation showing the bolt work in release position or after it has conditioned the obstructing means for 10 automatic movement to obstructing position following the return of the bolt work to securing position.

Figure 9 is a view showing the obstructing means in protecting position to which it is 15 automatically moved following movement of the bolt work from the position shown in Figure 8.

Figure 10 is a sectional plan taken on line 10a—10a of Figure 4

20 Figure 11 is a fragmentary elevation illustrating the position automatically assumed by a locking device for preventing unauthorized release of the time obstructing means should the spindle of the combination lock 25 be driven in by persons attempting to gain access to the safe or vault.

Figure 12 is a sectional plan taken on line 12a—12a of Figure 11.

30 Figure 13 is a plan view illustrating a detached portion of the bolt work obstructing means; and

35 Figure 14 is a detailed perspective view of a control lever for moving the obstructing means for the timing mechanism to and from operating position.

Similar reference numerals throughout the several views indicate the same parts.

The present invention is designed to afford 40 a safeguard, particularly against daylight holdups of bank vaults, safes and the like by holding in check the bolt work or securing mechanism for locking the door of the vault for a predetermined length of time after the combination or other controlling means has 45 been released whereby to foil any attempt of bandits or bank robbers in gaining immediate access to the contents of the vault or safe upon entering the bank.

50 The invention embodies generally a primary and a secondary or auxiliary control means for controlling the locking or securing mechanism of a closure for a safe, vault or other container with the primary means 55 arranged to be set for operation for variable time periods to effect release of the securing means at the ends of said periods, the secondary control means acting to prevent or delay operation of the primary means and 60 being preferably in the nature of means making it necessary for an unauthorized person to obtain certain information of a confidential nature before he can successfully release the secondary control means. The primary 65 control means may be considered as a part

of the securing or locking mechanism which it controls.

The secondary control means in the present instance is preferably shown as a combination lock, but may constitute other 70 means, if desired. The primary control means preferably constitutes a suitable timing mechanism and is shown in duplicate so that if one of the devices fails to operate the other can be relied on to function in the 75 desired manner. The timing mechanism is under the guard or protection of the secondary control means or combination lock and cannot begin operation until the combination is successfully operated. The securing 80 mechanism under the control of the timing mechanism preferably includes suitable bolt work for the door or closure of the container and obstructing means therefor adapted upon release of the bolt work to be conditioned thereby for automatic movement to obstructing position when the bolt work is cast or returned to securing position. The bolt work obstructing means constitutes that portion of the securing mechanism which 85 is released by the timing mechanism when the latter has operated for a predetermined period to be determined by the person having authority to control the operations of the mechanism.

In the present embodiment of the invention, 10 represents conventionally a safe or vault having a door or closure provided on its inner face with rearwardly projecting ribs or plates 12 in which are slidably mounted suitable means for guarding the closure 90 preferably comprising the bolts 13 shown in locking position in Figure 1. The bolts are connected by pins 15 with a vertically disposed bar 14 which is adapted to actuate the bolts simultaneously, the bar being moved by any suitable means such as a handle 16 and crank arm 17 having its free end disposed between the lugs 18 of the bar as shown in Figure 1. The bar is provided with a 95 laterally extending rod or projecting element 19 guarded by protecting mechanism comprising in part a suitable obstructing element 20 preferably in the form of a pivoted dog mounted within a casing 21 secured on the back of the door 11 and containing the combination lock and timing mechanism. The casing is provided with a door 22 hinged thereon, which is provided with a transparent panel 23 through which the timing mechanism is rendered visible. The casing is spaced slightly from the door, preferably by a plurality of rubber or other yieldable spacing members 24 as shown in Figure 2 which afford a certain degree of protection 100 to the timing mechanism by partially absorbing the blows to which the door 11 may be subjected from time to time.

The upper part of the casing containing 105 the combination lock or auxiliary control 110

means is preferably provided with a separate closure comprising a frame 25 carrying a transparent panel 26 through which the combination lock is rendered visible, the frame 5 being secured by screws 27 threaded into lugs 28 on the casing.

The usual knob and dial plate for the combination lock are indicated at 29 and 30, respectively, being provided with a spindle 31 projecting through the closure 11 into the container and through a sleeve 32 secured to the casing and rotatably supporting any desired number of tumblers 33 having notches 34 adapted to be brought into registry as indicated in Figures 5 and 6 before successful operation of the combination can be effected. A disk 35 is secured upon the spindle 31 to rotate therewith and is provided with an inwardly extending pin or lug (not shown) for operating the tumblers in the usual manner. The disk 35 is provided with a hub 36 adapted to project through a slot 37 in a lever or operating member 38, the purpose of which will presently appear. A washer 39 is carried by the hub to prevent outward displacement of the lever and a semi-circular spring 40 is held in a groove formed in the hub whereby the washer and lever are held against displacement longitudinally of the spindle. A key 41 connects the hub of the disk 35 with the spindle whereby rotation of the latter effects rotation of the disk and the tumblers as well. The lever or operating member 38 is provided for the purpose of moving the obstructing means for the timing or primary control mechanism to and from obstructing position, these positions being shown respectively in Figures 4 and 5.

The timing devices, two of which are shown, may constitute any suitable clock-driven or other desired mechanism for controlling the release of the dog or pivoted obstructing member 20, provided for guarding the bolt work as will be hereinafter described. The timing devices operate independently of each other and either of them will effect release of the bolt work obstructing means, should the other fail to operate.

Each timing device comprises a rotatable dial 42 having graduations 43 representing any divisions of time desired, such for example, as hours, shown in the present instance as divided into ten minute periods. A fixed pointer or index member 44 is arranged to correspond to the zero position of the dial when the latter is in rundown position. Previous to closing and locking the safe or vault the dials are set for a predetermined period, determined by the officials in charge, being shown set in Figure 4 for a period of two hours merely by way of example. The setting is effected through the medium of a suitable key adapted to be inserted upon the motor driven arbor 45 for winding the mechanism, through openings in the door panel,

the usual train of gears being provided, as shown, for driving the dials which are adapted to rotate counterclockwise as shown in Figure 4. The usual escapement wheel is indicated at 46 and the pallet for controlling the same is shown at 47. When the vault door is closed and locked and the combination destroyed, the several controlling mechanisms will be in the position shown in Figure 4, in which the previously set timing mechanism is prevented from operation by obstructing the movement of the pallets 47, which is done through the medium of a pair of fingers or rods 48 depending from a slide bar 49 movable upon a pair of spaced members 50, Figure 12, said bar being held in position and guided by a pair of screws 51 extending through slots 52 of the bar and threaded into the spaced members 50. The slide bar is provided with a laterally projecting pin 53 extending into a slot 54 in the lever 38, the latter constituting the operating means for moving the slide whereby to move the depending fingers 48 into and out of obstructing position with respect to the pallets 47 of the timing mechanism as shown respectively in Figures 4 and 5.

The lever 38 which is of the floating type, is under the control of the combination lock and cannot be moved to effect release of the timing mechanism until the combination lock has been successfully operated. On the other hand when the combination is destroyed, the lever is automatically returned to the central raised position shown in Figure 4 in which it serves as a guard to prevent release of the timing mechanism through shifting of the slide 49, release of which might otherwise be effected by a burglar in jarring the slide out of securing position or by tipping the safe or container to one side and permitting the slide to shift by gravity to said release position. The lever is provided with a projecting lug 55 above which extends laterally from the lever a finger 56 adapted to drop into the notches 34 of the tumblers, only when they are all brought into registry, as takes place when the combination is successfully operated. The raising of the lever from the release position shown in Figures 5 and 6 is effected by a cam 57 forming one side of a notch 58 in the disk 35, which operates the tumblers and which is operated by the spindle 31. In destroying the combination, the cam 57 will move into engagement with the bottom of the lug 55 of the lever and raise the latter from the position shown in Figure 6 to that shown in Figure 4, and during this operation the finger is moved out of the notches 34 of the tumblers so that continued rotation of the dial plate will destroy the combination by shifting the tumblers one relative to another, to move the notches thereof out of registry. After the lever has been lifted to the position shown in Figure 4, con-

tinued rotation of the disk 35 will move the notch therein out of registry with the lug 55 and although it may be returned to register therewith, the lever will not drop unless all 5 of the notches are again brought into registry. It will be seen therefore that the combination must be successfully operated before the lever can be swung from the central raised position shown in Figure 4 in which it blocks 10 release of the slide 49 and fingers 48 which guard the timing mechanism. The tumblers therefore constitute the operating means for the lever, becoming effective for this purpose as soon as the finger 56 drops into the 15 notches, as shown in Figure 6. From this position, turning of the dial spindle will move all of the tumblers in unison and the lever will be shifted to the release position shown in Figure 5, from which it may be 20 returned to central position by rotating the spindle in the opposite direction.

When the safe or vault is locked and the combination destroyed the lever is guarded by a stop lug or abutment 59 projecting from 25 the wall of the casing at the right side of the finger 56, making it impossible to shift the lever to effect release of the timing mechanism. This safety means is provided as a 30 precaution against jarring the lever to release position by any method which may be employed by a burglar, as by dynamiting the safe, in which case the effect of the explosion might cause the lever to shift from the position shown in Figure 4 if means were not 35 provided to prevent such movement. The notches 34 of the tumblers are deep enough to permit the finger 56 when operating in the notches to move under and clear the lug 59 upon rotation of the tumblers clockwise from 40 the position shown in Figure 6. Return of the finger 56 from the position shown in Figure 5 to that shown in Figure 6 takes place before the cam 57 begins to raise the lever, through engagement with the bottom of the 45 lug 55 thereon.

The dog or obstructing member 20 constituting a portion of the door securing mechanism has associated therewith an arm 60 provided with a laterally projecting sleeve or 50 tubular portion 61 pivoted upon a stud 62 having a portion 63 threaded into the rear wall of the casing 21 as shown in Figure 10. The dog 20 is pivoted upon the sleeve 61 of the arm to swing thereon relatively to 55 the arm. A washer 64 serves to prevent displacement of the arm and the dog, the washer being retained by a screw 65 threaded into the end of the stud 62 as indicated in Figure 10. The arm is adapted to support the dog 60 in the obstructing position indicated in Figures 4 and 9 through the medium of a latch 66 pivoted upon the dog at 67 and having its upper end held in a notch 68 of the arm by a pin 69 disposed within a recess formed in 65 the dog, the pin being actuated into engage-

ment with the latch by a spring 70 as shown in Figure 4.

The means for holding the arm 60 in position to maintain the dog in obstructing position comprises a latch member 71 having a tongue or shoulder 72 adapted to extend under a pin 73 projecting outwardly from the arm, the pin being preferably provided with a V-shaped portion 74 to facilitate cooperation between the pin and latch in the holding and releasing of the dog. The latching member 71 is detachably connected with a slide 75 by means of a screw 76. The opposite ends of the slide are guided in suitable brackets 77 on the side walls of the casting 71. The slide is provided with upstanding arms 78 disposed in the path of laterally projecting pins 79 carried by and adapted to be rotated with the dials 42 of the timing mechanism. The latch member 71 is normally held in position to support the arm 60 and dog 20 by a plunger 80 pressed outwardly by a spring 81 in a tubular member 82 carried by one of the brackets 77 as shown in Figure 5, the outer end of the plunger being in constant engagement with a lug 83 on the latch member whereby the arms 78 of the slide are urged in the direction of the pins 79 projecting from the dials 42. The latch member 71 is thereby held in supporting relation with respect to the arm 60 and dog 20 until moved to release position by the pins 79 revolving with the dials when the latter are rotated counter clockwise from the set 100 position shown in Figure 4 to the release position shown in Figure 5, in which the dog and its supporting arm are shown in their lowest position and to which they fall by gravity when released to clear the bolt work element 19. The bolt work is thus freed from obstruction and may be operated to unlock the closure by turning the handle 16 on the outside of the safe door.

When the dog 20 is released by the latching member 71 so that it is free to drop by gravity, the latch 66 for connecting the dog with the arm is automatically moved to release position through engagement of the angular portion 84 of the latch with the bottom wall of the casing, whereby the latch is swung upon its pivot to clear the arm as indicated in Figures 5 and 8.

As previously stated, means is provided whereby the bolt work is moved to release position to condition the dog for movement automatically to obstructing position as soon as the bolt work is returned to locking position. In moving the bolt work to release position the member 19 is projected through an opening 85 in the casing 21 to the extreme 120 position indicated in Figure 8. In moving to this position said member is adapted to strike a rod 86 which is guided by the dog and which, at its opposite end, is provided with a bevelled or cam surface 87 which is forced 125 into engagement with the latch member 71 as shown in Figure 8.

under a pin 88 projecting from the arm 60, whereby the pin is raised to move the arm to the position shown in Figure 8. The pin projects through a slot 89 in the arm and into a recessed portion 90 of the latter in which is disposed a spring 91 preferably of the leaf type as shown in Figure 7. The outer end of the spring is anchored in a slot formed in the dog and its opposite end rests upon the pin 88 so that when the rod is driven beneath the pin by the member 19, the spring becomes tensioned in the raising of the arm. The purpose of thus raising the arm when moving the bolt work to release position is to 15 elevate the outwardly projecting pin 73 of the arm so that upon setting the dials by movement from the position shown in Figure 5 to that shown in Figure 4, the slide 75 is freed for movement to the left by the spring 20 81 whereby the shoulder 72 of the latching member 71 is moved under the pin 73 of the arm to hold the latter in elevated position. This is the position to which the arm is automatically moved by the element 19 of the bolt 25 work. As long as the element 19 remains in the position shown in Figure 8, the dog 20 will occupy the position shown in this figure. However, immediately upon casting the bolt work and withdrawing the element 19, the 30 spring 91 will automatically move the dog from the position shown in Figure 8 to that shown in Figure 9, and the bolt work cannot be released until the timing mechanism is first released by operating the combination 35 lock, after which the timing mechanism must operate for the period for which it was previously set before the safe can be opened.

The rod 86 which tensions the spring 91 is prevented from turning by a screw 92 engaging a flattened portion 93 of the rod as shown in Figure 10.

Safety means is provided for preventing the dropping of the dog and release of the bolt work in case dynamite or other materials are exploded within the safe with the idea of damaging the timing or bolt work obstructing mechanism sufficiently to permit release of the bolt work in order to gain access to the safe. In this connection it will be noted that 45 the casing 21 is secured to the closure 11 by a plurality of studs or screws 94 having heads 95 countersunk within the wall of the casing as shown in Figure 10, the casing having the yieldable spacing members 24 between it and 50 the closure and through which the studs are extended. At the bottom of the casing and behind the dog 20, a relatively thin plate 96 is disposed in front of the heads of the studs 94, the plate being secured to the rear wall of 55 the casing by a screw 97 as shown in Figure 10. The plate is provided at its right end as viewed in Figure 9 with a slot 98 occupying a position immediately below the obstructing end of the dog when the latter is in raised or 60 obstructing position. The portion of the

plate below the slot, indicated at 99, lies directly in front of the head of the lower right hand securing stud 94. In cases where dynamite or other materials are exploded within the safe with the idea of displacing or releasing the bolt work protecting mechanism, the force of the explosion will result in driving the casing toward the door or closure 11 since the resistance of the yieldable spacing members 24 will be readily overcome, the result being that the head 95 of the lower right hand stud will force the plate portion 99 inwardly or to the approximate position shown by dotted lines in Figure 10, in which position it will lie beneath the dog to prevent its dropping and consequently preventing release of the bolt work.

Safety means is also provided for preventing release of the timing mechanism, should the spindle of the combination lock be driven in, as is often done by burglars attempting to gain access to safes or vaults containing money or other valuables. This means is adapted to prevent jarring or otherwise effecting movement of the slide 49 and depending fingers 48 thereon from obstructing position with relation to the timing mechanism as indicated at Figure 4. In this connection it will be understood that should the spindle be driven in, the lever 38 thereon will also be forced inwardly along with the spindle without interfering with the slide 49, since the headless pin 53 thereon projecting within the slot 54 of the lever will not interfere with the inward movement of the latter. The means for holding the slide 49 against movement from protecting position after the spindle has been driven in comprises a latch 100 pivoted upon the rear wall of the casing 21 at 101 and normally held in non-latching position by a pin 102 projecting from the lever beneath the latch as shown in Figures 4 and 5. The latch when released by displacement of the lever is forced downwardly by a spring 103 to engage a pin 104 extending from the slide 49 into the space between the supports 50 of the latter as shown in Figures 11 and 12. The slide is thus positively held against release by the latch and the burglar's attempt to gain access to the contents of the safe by driving in the spindle and releasing the obstructing means for the timing mechanism is prevented.

A guard plate 105 is disposed in front of the latch and is secured to the casing by screws 106 as shown in Figure 11. The guard plate is provided to prevent raising of the latch to release the slide by the use of a wire or other instrument inserted through the closure 11 after the spindle is driven in. The guard plate is cut away at 107 to permit movement of the pin 102 on the lever 38 as the latter is moved to and from the positions indicated in Figures 4 and 5. The spring 103 for depressing the latch is preferably soldered or other-

wise secured to the base portion 108 of an arm 109, which is slotted at 110 to receive a key (not shown) by which the combination may be changed when desired, the key being inserted through said slot and into registering slots 111 formed in the tumblers 33.

In the operation of the lock mechanisms, assuming that the vault or safe door is open and that it is desired to close and lock the same, the operator will first set the timing mechanism to operate for a predetermined period after the combination lock is released, such period or periods preferably being for relatively short intervals during banking hours or while business is being transacted, whether in the case of banks, stores or manufacturing establishments employing the present lock mechanism for protection against robbery. On the other hand at night or during holidays the timing mechanism will of course be set for longer periods. It will be understood as stated above that when the bolt work is moved to release position, the arm 60 will be raised by the rod 86 through movement thereof by the bolt work element 19 as shown in Figure 8, thus raising the pin 73 to permit the tongue of the latch member 71 to move under the pin, this operation taking place simultaneously through the action of the spring 81 upon rotating the dials counter-clockwise from the zero position to the desired "set" position. The door of the safe or vault is then closed and the bolt work cast and as the element 19, moving with the bolt work, clears the end of the dog 20, the previously tensioned spring 91 thereof will automatically raise the dog to the obstructing position shown in Figures 4 and 9. The safe thus becomes locked and guarded by the obstructing dog under the control of the timing mechanism. Before the safe can again be opened, the combination lock must be brought to release position, following which the lever 38 will drop from the protecting position shown in Figure 4 to that shown in Figure 6, after which the knob 29 of the dial plate will be turned to move the lever to the position shown in Figure 5. The lever in turn moves the slide 49 and depending fingers 48 to clear the pallets 47 whereby the clock mechanism immediately begins operation. In approaching the zero position or the end of the predetermined period for which the time devices were previously set, the pins 79 on the rotating wheels 42, will engage the upstanding arms 78 of the slide 75 and begin movement of the latch member 71 to the right as viewed in Figure 4. As soon as the tongue or shoulder 72 of the latch member clears the pin 73, the dog 20 and parts associated therewith will drop by gravity to release position and permit the bolt work to be retracted so that the door or closure of the safe can be opened.

65 What I claim is:—

1. In combination, a container including a closure and locking means therefor, including relatively movable securing and protecting mechanisms, the latter being conditioned for movement automatically to obstructing position with respect to the former upon release of the former, whereby when the securing mechanism is moved to securing position the protecting mechanism will obstruct and prevent release of the securing mechanism. 70

2. In combination, a container including a closure and locking means therefor, including relatively movable securing and protecting mechanisms, the latter being conditioned for movement automatically to obstructing position with respect to the former upon release of the former, whereby when the securing mechanism is moved to securing position the protecting mechanism will obstruct and prevent release of the securing mechanism 80 and means for controlling the operations of said mechanisms. 85

3. In combination, a container including a closure and locking means therefor, including relatively movable securing and protecting mechanisms, the latter being conditioned for movement automatically to obstructing position with respect to the former upon release of the former, whereby when the securing mechanism is moved to securing position 90 the protecting mechanism will obstruct and prevent release of the securing mechanism, and timing mechanism adapted after operation for a predetermined period to effect release of said protecting mechanism. 95

4. In combination, a container including a closure, securing means for the closure including relatively movable devices, one of which embodies means adapted to be actuated by the other whereby the former is conditioned for movement to obstructing position with respect to the latter when the latter is moved to a predetermined position and means operable to control release of the obstructing device. 105

5. In combination, a container including a closure, securing means for the closure including relatively movable devices, one of which is adapted to be conditioned for automatic movement to obstructing position with relation to the other when the latter is moved to release position and means operable to prevent release of the obstructing device for variable periods of time. 110

6. In combination, a container including a closure, securing means for the closure including relatively movable devices, one of which is adapted to be conditioned for automatic movement to obstructing position with relation to the other when the latter is moved to release position and timing mechanism adapted after operation for a predetermined period to release said obstructing device. 120

7. In combination, a container including 125

5 a closure, securing means for the closure including relatively movable devices one of which comprises means adapted to be actuated by the other whereby the former is conditioned for automatic movement to obstructing position with respect to the latter under predetermined conditions of operation and selective control means for guarding said securing means when the latter is in 10 protecting position with respect to the closure.

15 8. In combination, a container including a closure, securing means for the closure including relatively movable devices one of which comprises means adapted to be actuated by the other whereby the former is conditioned for movement to obstructing position with respect to the latter under predetermined conditions of operation and timing 20 mechanism adapted after operation for a predetermined period to release the obstructing device whereby to permit release of the device obstructed thereby.

25 9. In combination, a container including a closure, securing means therefor including relatively movable devices, one of which is adapted to releasably obstruct the other whereby to prevent opening of the closure, a part for releasing said obstructing device 30 movable relative thereto timing mechanism operable for a predetermined period and adapted at the end of said period to operate said part whereby to effect release of said obstructing device and means operable independently of said part and of the securing 35 means adapted to be moved when the closure is in locked position to prevent operation of said timing mechanism.

40 10. In combination, a container including a closure, securing means therefor including relatively movable devices one of which is adapted to releasably obstruct another whereby to prevent opening of the closure, a part for releasing said obstructing device 45 movable relative thereto primary means operable for a predetermined period and adapted at the end of said period to operate said part whereby to release said obstructing device and auxiliary means including a combination lock independently operable with respect to said part and said securing means and adapted when the combination is destroyed with the closure in closing position to be moved by the combination lock into position to prevent operation of said primary means.

55 11. In combination, a safe including a closure, securing mechanism therefor, a lock, timing mechanism adapted to control the securing mechanism and obstructing means for the timing mechanism independent of the securing mechanism controlled thereby including relatively movable devices one of which comprises a lever under control of the 60 lock and the other a reciprocally mounted

part movable to obstructing position by the lever when the closure is in closed position.

12. In combination, a safe including a closure, securing mechanism therefor, timing mechanism for controlling said securing mechanism, a combination lock including an operating spindle and means for obstructing the timing mechanism including a member arranged to swing about the axis of the spindle and to be operated thereby. 70

75 13. In combination, a safe including a closure, securing mechanism therefor, timing mechanism for controlling said securing mechanism, a combination lock including an operating spindle, an abutment adjacent the lock and means for obstructing the timing mechanism including a member arranged to swing about the axis of the spindle and adapted when the combination is destroyed to be held in check by said abutment. 80

85 14. In combination, a safe including a closure, securing mechanism therefor, timing mechanism for controlling said securing mechanism, a combination lock including an operating spindle and means for obstructing the timing mechanism including relatively movable parts one of which is operatively associated with the spindle and arranged to have a sliding movement and a swinging movement about the axis thereof. 90

95 15. In combination, a safe including a closure, securing mechanism therefor, timing mechanism for controlling said securing mechanism, a combination lock including an operating spindle, means operatively connected with the spindle for obstructing the timing mechanism including relatively movable parts one of which is arranged to have a sliding movement to inoperative position and a swinging movement about the axis of the spindle while operating another of said parts, and means for preventing release of the first mentioned part when the combination is destroyed. 100

105 16. In combination, a safe including a closure, securing mechanism therefor, timing mechanism for controlling the securing mechanism, a combination lock including an operating spindle and means for obstructing the timing mechanism including a member adapted to swing about the axis of the spindle and arranged to be moved by and relative to the spindle. 110

115 17. In combination, a safe including a closure, securing mechanism therefor, timing mechanism for controlling the securing mechanism, a combination lock including an operating spindle, means for obstructing the timing mechanism including a member adapted to swing about the axis of the spindle and arranged to be moved by and relative to the spindle and means for preventing operation of said member when the combination is destroyed. 120

125 18. In combination, a safe including a clo- 130

sure, securing mechanism therefor, timing mechanism for controlling the securing mechanism, a combination lock including a spindle and a series of tumblers provided with notches adapted to be brought into registering relation when the lock is in release position, means for obstructing the timing mechanism including a member operatively associated with the spindle and arranged to swing about and to move relative to its axis and having a portion adapted when the lock is in release position to engage the tumblers within said notches, whereby upon rotation of the spindle in opposite directions the tumblers will swing said member to and from said obstructing position with respect to the timing mechanism.

19. In combination, a safe including a closure, securing mechanism therefor, timing mechanism for controlling the securing mechanism, a combination lock including a spindle and a series of tumblers provided with notches adapted to be brought into registering relation when the lock is in release position, means for obstructing the timing mechanism including a guard and an operating member therefor arranged to swing about and to move relative to the axis of the spindle and having a portion adapted when the lock is in release position to engage the tumblers within said notches, whereby rotation of the tumblers within said notches, whereby rotation of the tumblers in opposite directions will cause said member to move the guard to and from obstructing position with respect to the timing mechanism, means connected with the spindle for actuating said member to cause said portion to move out of said notches when the guard is in protecting position and the spindle is operated to destroy the combination and means for preventing operation of said member until the lock is subsequently moved to release position.

20. In combination, a safe including a closure, locking means for the closure including relatively movable mechanisms one of which is adapted to condition the other for automatic movement to obstructing position when moved to release the closure whereby upon locking the closure said conditioned mechanism will operate to obstruct the conditioning mechanism and means by which to effect release of the conditioned mechanism.

21. In combination, a safe including a closure, locking means for the closure including relatively movable mechanisms, one of which is adapted to condition the other for automatic movement to obstructing position when moved to release the closure whereby upon locking the closure said conditioned mechanism will operate to obstruct the conditioning mechanism and selective control

means for releasing the conditioned mechanism.

22. In combination, a safe including a closure, locking means for the closure including relatively movable mechanisms, one of which is adapted to condition the other for automatic movement to obstructing position when moved to release the closure whereby upon locking the closure said conditioned mechanism will operate to obstruct the conditioning mechanism, timing mechanism for releasing said conditioned mechanism after operation for a predetermined period including a part adapted to move into supporting engagement with said conditioned mechanism upon setting the timing mechanism and arranged to be moved by the latter at the end of said period to release position with respect to the conditioned mechanism. 75

23. In combination, a safe including a closure, locking means for the closure including relatively movable mechanisms, one of which is adapted to condition the other for automatic movement to obstructing position when moved to release the closure whereby upon locking the closure said conditioned mechanism will operate to obstruct the conditioning mechanism, timing mechanism for releasing said conditioned mechanism after operation for a predetermined period including a part adapted to move into supporting engagement with said conditioned mechanism upon setting the timing mechanism and arranged to be moved by the latter at the end of said period to release position with respect to the conditioned mechanism and selective control mechanism for guarding and releasing the timing mechanism. 80 90 95

24. In combination, a safe including a closure, locking means for the closure including relatively movable mechanisms, one of which is adapted to condition the other for automatic movement to obstructing position when moved to release the closure whereby upon locking the closure said conditioned mechanism will operate to obstruct the conditioning mechanism, timing mechanism arranged to operate for a predetermined period to effect release of the conditioned mechanism and selective control mechanism for guarding and releasing the timing mechanism. 105 110 115

25. In combination, a safe including a closure, protecting mechanism for the closure including relatively movable devices, one of which forms securing means for the closure and the other comprising obstructing means for the securing means arranged to be conditioned by the latter upon its release for automatic operation to obstructing position when the securing means is moved to closure securing position and means for releasing the obstructing means. 120 125

26. In combination, a safe including a closure, protecting mechanism for the closure including relatively movable devices, one of

which forms securing means for the closure and the other comprising obstructing means for the securing means arranged to be conditioned by the latter upon its release for automatic operation to obstructing position when the securing means is moved to closure protecting position and timing mechanism arranged to be set for operation for a predetermined period and adapted at the end of 10 said period to effect release of the obstructing means.

27. In combination, a safe including a closure, protecting mechanism for the closure including relatively movable devices, one 15 of which forms securing means for the closure and the other comprising obstructing means for the securing means arranged to be conditioned by the latter upon its release for automatic operation to obstructing position when the securing means is moved to protecting position, timing mechanism arranged to be set for operation for a predetermined period and adapted at the end of 20 said period to effect release of the obstructing means, a lock, and means under the control of the lock for preventing operation of the timing mechanism until the lock is moved to release position.

28. In combination, a safe including a closure, protecting mechanism for the closure including relatively movable devices, one of 30 which forms securing means for the closure and the other comprising obstructing means for the securing means arranged to be conditioned by the latter upon its release for automatic operation to obstructing position when the securing means is moved to closure 35 protecting position, timing mechanism arranged to be set for operation for a predetermined period and adapted at the end of said period to effect release of the obstructing means and selective control means arranged to normally obstruct operation of the timing mechanism.

29. In combination a safe including a closure, protecting mechanism for the closure including relatively movable devices, one of 45 which forms securing means for the closure and the other comprising obstructing means for the securing means arranged to be conditioned by the latter upon its release for automatic operation to obstructing position when the securing means is moved to closure 50 protecting position, timing mechanism arranged to be set for operation for a predetermined period and adapted at the end of said period to effect release of the obstructing means and means for normally obstructing operation of the timing mechanism including manually operable selective control means.

30. In combination, a safe including a closure, protecting mechanism for the closure including relatively movable devices, one 55 of which forms securing means for the clo-

sure and the other forming obstructing means for the securing means and embodying relatively movable parts including a spring and tensioning means therefor adapted to be operated by the securing means upon movement of the latter to release position whereby one of said movable parts is conditioned for movement automatically by the spring to obstructing position with respect to the securing means when the latter is moved to closure protecting position and selective control means for effecting release of said parts.

31. In combination, a safe including a closure, protecting mechanism for the closure including relatively movable devices one of which forms securing means for the closure and the other forming obstructing means for the securing means embodying a plurality of 60 relatively movable parts including an actuating member and a conditioning member therefor adapted to be operated by the securing means upon movement of the latter to release position whereby upon release of the conditioning member by movement of the securing means to closure protecting position one of said parts will automatically move to obstructing position with respect to the securing means and selective control means for effecting release of said part.

32. In combination, a safe including a closure, locking mechanism for the closure including bolt-work and obstructing means therefor comprising a spring and a plurality of relatively movable members, one comprising a holding member movable to tension the spring whereby to condition another of said members for movement automatically to obstructing position with relation to the bolt work when the latter is cast and a third member arranged for operation by the bolt work upon release of the latter to move the holding member to spring tensioning position at which it is arranged to support the second mentioned member in obstructing position and releasable means for guarding the holding member.

33. In combination, a safe including a closure, locking mechanism for the closure including bolt work and obstructing means therefor comprising a spring and a plurality of relatively movable members, one comprising a holding member movable to tension the spring whereby to condition another of said members for movement automatically to obstructing position with relation to the bolt-work when the latter is cast, a third member arranged for operation by the bolt work upon release of the latter to move the holding member to spring tensioning position at which it is arranged to support the second mentioned member in obstructing position and selective control means for guarding and releasing the holding member.

34. In lock mechanisms for closures, bolt

- work for protecting the closure, a pivoted dog movable to obstruct the bolt work and having a spring associated therewith, a holder for the dog movable to tension the spring, 5 a member adapted to be actuated by the bolt work upon movement of the latter to release position whereby to move the holder to spring tensioning position, the spring serving to automatically move the dog to obstructing position when the bolt work is cast, from which position the dog is adapted to drop by gravity when released, a latch for coupling the dog with the holder when it is moved to obstructing position and means 10 for releasing the latch upon dropping of the dog.
35. In lock mechanisms for closures, bolt work for protecting the closure, a pivoted dog movable to obstruct the bolt work and 20 having a spring associated therewith, a holder for the dog movable to tension the spring, a member adapted to be actuated by the bolt work upon movement of the latter to release position whereby to move the holder to 25 spring-tensioning position, the spring serving to automatically move the dog to obstructing position when the bolt work is cast, from which position the dog is adapted to drop by gravity when released, a latch for 30 coupling the dog with the holder when it is moved to obstructing position, means for releasing the latch upon dropping of the dog and releasable securing means for the holder.
36. In combination, a safe including a closure, securing mechanism therefor, a combination lock including an operating spindle, and means for obstructing the securing mechanism including a member arranged to swing about the axis of the spindle and to be operated thereby.
37. In combination, a safe including a closure, securing mechanism therefor, a combination lock including an operating spindle, an abutment adjacent the lock and means 45 for obstructing the securing mechanism including a member arranged to be operated by the spindle to swing about the axis thereof and adapted when the combination is destroyed to be held in check by said abutment.
- 50 38. In combination, a safe including a closure, securing mechanism therefor, a combination lock including an operating spindle and means for obstructing the securing mechanism including relatively movable parts one of which is operatively associated with the spindle and arranged to have a 55 swinging movement about the axis thereof.
39. In combination, a safe including a closure, securing mechanism therefor, a combination lock including an operating spindle, means operatively connected with the spindle for obstructing the securing mechanism including relatively movable parts, one of which is arranged to have a sliding movement to inoperative position and a swinging
- movement about the axis of the spindle while operating another of said parts and means for preventing release of the first mentioned part when the combination is destroyed.
40. In combination, a safe including a closure, securing mechanism therefor, a combination lock including a spindle and a series of tumblers provided with notches adapted to be brought into registering relation when the lock is in release position, means for obstructing the securing mechanism including a member operatively associated with the spindle and arranged to swing about and to move relative to its axis and having a portion adapted when the lock is in release position to engage the tumbler within said notches whereby upon rotation of the spindle in opposite directions the tumbler will swing said member to and from obstructing position with respect to the securing mechanism.
41. In combination, a safe including a closure, securing mechanism therefor, a combination lock including a spindle and a series of tumblers provided with notches adapted to be brought into registering relation when the lock is in release position, means for obstructing the securing mechanism including a shiftable member and an operating member therefor arranged to swing about and to move relative to the axis of the spindle and having a portion adapted when the lock is in release position to engage the tumblers within said notches whereby rotation of the tumblers in opposite directions will cause 100 said member to move the shiftable member to and from obstructing position with respect to the securing mechanism, means connected with the spindle for actuating said member to cause said portion to move out of 105 said notches when the shiftable member is in protecting position and the spindle is operated to destroy the combination and means for preventing operation of said member until the lock is subsequently moved to release 110 position.
42. In combination, a container including a closure, securing means for the closure, protecting means for preventing unauthorized release of the securing means and means including a releasable obstructing member arranged to be conditioned by the force of an explosion within the container to guard said obstructing member against release said means including a projection extending inwardly from the closure and a member in the path thereof having one end fixed, the opposite end of which is swung to protecting position with respect to said obstructing member by said projection.
43. In combination, a container including a closure, securing means for the closure, a support within the container, a yieldable element interposed between the closure and support permitting the latter to be moved to 125

ward the closure under the force of an explosion within the container; an abutment on the closure, releasable protecting means for preventing unauthorized release of the securing means and a member on said support adapted upon movement of the latter toward the closure under the force of the explosion to be moved by said abutment into position to prevent release of said protecting means.

44. In combination a container including a closure, securing means therefor, releasable obstructing means for the securing means including timing mechanism, a device normally holding the timing mechanism in check, release means for said device including a spindle operable from the exterior of the closure and having a part for moving said device to release position and means arranged to automatically assume a position at which it will prevent release of said device should the spindle be driven in and said part displaced thereby.

45. In combination a container including a closure, securing means therefor, releasable obstructing means for the securing means, control means for checking release of the obstructing means including timing mechanism, a device normally holding the timing mechanism against operation, manually operable release means for said device and means under the control of said manually operable release means arranged to automatically assume a position at which it will maintain said device in position to hold the timing mechanism in check should the manually operable release means be removed with the closure in locking position.

46. In combination, a container including a closure, securing means for the closure, an obstructing element for the securing means, releasable holding means for the obstructing element, timing mechanism having a rotary part and driving means therefor adapted after operation of the driving means for a predetermined period to move said holding means to release position, a device spaced from and independent of said holding means in all positions of the latter, said device normally occupying a position at which it serves to hold the driving means in check and operating means for said device accessible from the exterior of the container and adjustable to move said device to and from said position when the closure is in closed position, said operating means being independent of the obstructing means in all of its positions.

47. In combination, a container including a closure, securing means therefor, releasable obstructing means for the securing means, timing mechanism for effecting release of the obstructing means, a releasable device for holding the timing mechanism in check, means including a spindle operable from the exterior of the container, and means serving to prevent release of said device in case the

spindle is driven in with the closure in locked position whereby to prevent release of the timing mechanisms.

48. Lock mechanism comprising securing means movable to and from locking position and protecting mechanism for the securing means arranged to be conditioned by the securing means when it is moved from securing position for movement automatically to obstructing position relative to said securing means upon return of the latter to locking position.

49. Lock mechanism comprising securing means movable to and from locking position, protecting mechanism for the securing means arranged to be conditioned by the securing means when it is moved from securing position for movement automatically to obstructing position relative to said securing means upon return of the latter to locking position, and a releasable holding device for the protecting mechanism arranged to automatically move to holding position when said protecting mechanism is moved to obstruct said securing means.

50. Lock mechanism comprising securing means movable to and from locking position, protecting mechanism for the securing means arranged to be conditioned by the securing means when it is moved from securing position for movement automatically to obstructing position relative to said securing means upon return of the latter to locking position, a device for holding the protecting mechanism in position to obstruct the securing means and a timing mechanism arranged after operation for a predetermined period to release said holding device whereby to permit release of said protecting mechanism.

51. Lock mechanism comprising securing means movable to and from locking position and protecting mechanism for the securing means embodying relatively movable parts including a spring and tensioning means therefor arranged to be operated by the securing means upon movement of the latter from locking position whereby one of said movable parts is conditioned for movement automatically by the spring to obstruct the securing means when the latter is returned to securing position.

52. Lock mechanism comprising securing means movable to and from locking position and protecting mechanism for the securing means comprising a spring and a plurality of relatively movable members, one forming a pivoted member movable to tension the spring whereby to condition another of said members for movement automatically to obstructing position with relation to the securing means when the latter is moved to locking position and a third member arranged for operation by the securing means upon moving the latter from locking position whereby the pivoted member is moved to spring tensioning.

position at which it is arranged to support the second mentioned member in position to obstruct the securing means.

53. Lock mechanism for guarding bolt work comprising a pivoted dog movable to obstruct the bolt work and having a spring associated therewith, a holder for the dog movable to tension the spring, a member arranged to be actuated by the bolt work upon movement of the latter to release position whereby to move the holder to spring tensioning position, the spring serving to automatically move the dog to obstructing position when the bolt work is cast, from which position the dog is movable to clear the bolt work, a latch for automatically coupling the dog with the holder when it is moved to obstructing position, means for releasing the latch upon movement of the dog from obstructing position and releasable means for supporting the holder in position to maintain the guard in obstructing position.

54. Locking means for a safe closure comprising, securing means, a lock, normally inactive timing mechanism including power means and a rotary element driven thereby adapted to control the securing means and obstructing means for the power means including relatively movable parts, one of said parts being arranged for movement by the lock to actuate the other when the closure is in closed position and both being spaced from and independent of the securing means in all positions of the latter.

55. Locking means for a safe closure comprising, securing mechanism including a guard and a releasable holding element therefor, a lock, timing mechanism comprising a rotary element for releasing the holding element and releasable power means for operating the rotary element, and means independent of the guard and holding element for obstructing and releasing the power means comprising a movable part for holding the power means in check and an operating part for said movable part arranged to be actuated by the lock to obstructing position when the closure is in closed position and to release the power means when the lock is moved to unlocked position.

56. The combination of a container including a closure, securing mechanism for the closure, a releasable guard for the securing mechanism, a retaining member operating to hold the guard against movement from securing position, normally inactive timing mechanism including an operating member for moving the retaining member, said operating member normally occupying a position in spaced relation to the retaining member and adapted after operation of the timing mechanism for a predetermined period to engage and move the retaining member into position to clear the guard, and releasable means independent of the securing

means serving to hold the timing mechanism in check with the operating member spaced from said retaining member.

57. The combination of a safe having a door, bolt work for securing the door, guard means for the bolt work operating to hold the same against release, a combination lock mechanism, timing mechanism arranged after operation for a predetermined period to release said guard means, and means under the control of the combination lock mechanism including a part spaced from and independent of the guard means arranged upon destroying the combination to move into position to hold the timing mechanism in check.

58. The combination of a safe having a door, bolt work for securing the door, guard means for the bolt work movable automatically into protecting position with relation thereto upon locking the door, a combination lock mechanism, normally inactive timing mechanism arranged after operation for a predetermined period to release said guard means, and means under the control of the combination lock mechanism including a part spaced from and independent of the guard means arranged upon destroying the combination to move into position to hold the timing mechanism in check.

59. The combination of a safe having a door, a bolt for securing the door, guard means for the bolt movable relative thereto and operating to hold the same against release, a combination lock mechanism, normally inactive timing mechanism arranged after operation for a predetermined period to release said guard means, and means under the control of the combination lock mechanism including a part spaced from and independent of the guard means operating upon destroying the combination with the door in closed position to move into engagement with and to hold the escapement means of the timing mechanism against operation.

60. The combination of a safe having a door, a bolt for securing the door, guard means for the bolt movable automatically into position to protect the latter when it is moved to locking position, a combination lock mechanism including an operating spindle and tumblers associated therewith, normally inactive timing mechanism including a part arranged after operation for a predetermined period to release said guard means, and means under the control of the tumblers of said combination lock arranged upon destroying the combination with the door in closed position to move into obstructing position with respect to the escapement means of the timing mechanisms.

61. The combination of a safe having a door, locking mechanism for the door, guard means movable to effect release of said locking mechanism, normally inactive timing

- mechanism having associated therewith a member arranged after the timing mechanism has been released and operated for a predetermined period to move into operative engagement with the guard means to release the same whereby to release the locking mechanism, and obstructing means arranged to hold the timing mechanism in check in advance of the movement of said member by 5 the timing mechanisms into position to engage said guard means, said obstructing means being operated to obstructing position after the door has been closed.
62. In combination, a safe having a door, 15 locking mechanism for securing the door including a self operating device rendered operative for movement to securing position upon locking the door, holding means for maintaining said device in locking position, 20 normally inactive timing mechanism including a part arranged after operation for a selected period from a predetermined position to start movement of said holding means to release position, obstructing means for 25 holding the timing mechanism in check with said part at said predetermined position, and means operable from the exterior of the door when the latter is in closed position to move said obstructing means into position to obstruct the timing mechanism.
63. Lock mechanism for a safe door, comprising a bolt, guard means for the bolt movable automatically into protecting position with respect to the bolt upon locking the 35 door, normally inactive timing mechanism including a device spaced from said guard means and arranged after operation of the timing mechanism for a predetermined period to engage and move the guard means 40 to release position whereby to release the bolt, a combination lock for the door comprising an operating spindle and tumblers actuated thereby, an obstructing device engaging the escapement means of the timing mechanism to hold the latter in check when the door 45 is locked, and means under the control of the spindle for releasing said obstructing device when the combination is successfully operated.
- 50 64. Lock mechanism for a protecting structure, comprising relatively movable devices, one a locking device and the other a guard therefor movable automatically to protecting position with respect to the locking device upon movement of the latter to locking position, a retaining member for said guard, normally inactive timing mechanism including a part arranged after operation for a selected period from a predetermined position to engage and move said retaining member to release said guard, obstructing means for holding the timing mechanism in check with said part at said predetermined position, and means operable when said protecting structure is in locked position to move 55
- said obstructing means both to and from obstructing position.
65. Lock mechanism for a protecting structure, comprising relatively movable guard and locking devices, said guard device being 70 conditioned for movement automatically to obstructing position with respect to the locking device upon movement of the latter to release said protecting structure, retaining means for said guard device operating to 75 engage and hold the latter when it is moved to obstruct the locking device, and timing mechanism arranged after operation for a predetermined period to release said retaining means whereby to effect release of said 80 guard device.
66. The combination of a safe door having securing means therefor, guard means for protecting the securing means and held by the latter against movement to protecting 85 position when the securing means is in non-securing position and movable automatically to protecting position upon moving the securing means to securing position, a combination lock, normally inactive timing mechanism having a part associated therewith arranged after operation of said timing mechanism for a predetermined period to release said guard means to effect release of 90 the securing means, and means controlled by the combination lock for holding the timing mechanism in check in advance of said period of operation, said holding means being responsive to the combination lock and moving into position to hold the timing mechanism in check upon destroying the combination of the lock and freeing the timing mechanism for operation upon successful 95 operation of the combination lock.
67. The combination of a safe door having 100 locking means therefor, spring pressed guard means for protecting the locking means and held by the latter against movement to protecting position when the locking means is in nonsecuring position, said guard means being 105 movable automatically to protecting position upon moving the locking means to securing position, timing mechanism arranged after operation for a predetermined period to effect release of the guard means, a combination lock having notched tumblers, and means for holding the timing mechanism in check in advance of said period of operation, said holding means including a part movable into the notches of the tumblers upon 110 successful operation of the combination lock to release the timing mechanism and effective upon destroying the combination of the lock with the door in closed position to return 115 to obstructing position with respect to the timing mechanism.
68. The combination of a safe door having locking means therefor, guard means for protecting the locking means and held by the latter against movement to protecting posi- 120
- 125
- 130
- 135

- tion when the locking means is in non-securing position, said guard means being movable automatically to protecting position upon moving the locking means to securing position, timing mechanism arranged after operation for a predetermined period to effect release of the guard means, a combination lock including tumblers and a spindle having a notched operating member for the tumblers, 10 and a device for holding the timing mechanism in check in advance of said period of operation, a portion of said device moving into the notch of the tumbler operating member upon successful operation of the 15 combination lock to permit release of the timing mechanism, the combination of the lock being capable of being destroyed with the safe door in closed position, and such destruction being effective to move said portion out of said notch in the operating member 20 and to return said device to position to hold the timing mechanism in check.
69. The combination of a safe door having locking means therefor, guard means for protecting the locking means and held by the latter against movement to protecting position when the locking means is in non-securing position and movable automatically to protecting position upon moving the locking 25 means to securing position, timing mechanism having a part spaced from said guard means and movable after the timing mechanism has operated for a predetermined period to engage and shift the guard means 30 from protecting position whereby to release the locking means, a combination lock, and means under the control of said lock arranged upon destroying the combination when the door is closed to move into position to hold 35 the timing mechanism in check in advance of said predetermined period of operation and moving upon successfully operating the combination to release the timing mechanism for operation for said period.
- 40 70. The combination of a safe door having locking means therefor, guard means for protecting the locking means, timing mechanism including escapement mechanism, said timing mechanism being effective to release the 45 guard means to effect release of the locking means, a combination lock including notched tumblers and a spindle having a notched operating member for the tumblers, and a device engaging said escapement mechanism to 50 hold the timing mechanism in check when the combination lock is in locked position, said device including parts arranged to move into the notches of the tumblers and operating member upon successfully operating the combination 55 whereby to release the escapement mechanism for operation.
71. The combination with a safe door having locking means mounted thereon, of guard means for preventing unlocking movement of 60 said locking means, said guard means being 65

held in an ineffective position by the locking means when said locking means is in unlocking position, and being moved automatically to an effective position when said locking means is moved to locking position, a combination lock, timing mechanism effective after operation for a predetermined period to shift said guard means to an ineffective position to permit unlocking movement of said locking means, said timing mechanism including 70 a vibrating pallet and an escapement wheel controlled thereby, an obstructing member for contacting with said pallet to prevent vibration thereof and thus to hold said timing mechanism against operation, and means 75 controlled by said combination lock and effective upon successful operation thereof to shift said obstructing member to a non-obstructing position to permit vibration of said pallet and operation of said timing mechanism, said last named means being effective upon destroying the combination of the lock to move said obstructing member automatically to an obstructing position with respect 80 to said pallet.
